CLAIM

The ornamental design for a multi-segmented corridor light, as shown and described.

DESCRIPTION

FIG. 1 is a front view of a multi-segmented corridor light showing an embodiment of our new design;

FIG. 2 is a top side perspective view for the multi-segmented corridor light shown in FIG. 1;

FIG. 3 is a bottom side perspective view of the multi-segmented corridor light shown in FIG. 1; and,

FIG. 4 is a left side view of the multi-segmented corridor light shown in FIG. 1, and only the left side view is provided as the right side view is a mirror image.

The broken lines shown in the drawings represent portions of the multi-segment corridor light that form no part of the claimed design. A rear view has been excluded from the figures, as the rear view is flat and devoid of surface ornamentation.
